UNITED STATES PATENT OFFICE.

SAMUEL H. RICE, OF SAN FRANCISCO, CALIFORNIA, ASSIGNOR TO KALAMAZOO LOOSE LEAF BINDER CO., OF KALAMAZOO, MICHIGAN.

BINDER DEVICE.

1,278,506.

Specification of Letters Patent. Patented Sept. 10, 1918.

Application filed June 15, 1917. Serial No. 174,919.

To all whom it may concern:

Be it known that I, SAMUEL H. RICE, a citizen of the United States, residing at San Francisco, California, have invented 5 certain new and useful Improvements in Binder Devices, of which the following is a specification.

This invention relates to improvements in binder devices.

10 My improvements are especially designed by me for use in temporary binders or loose sheet holders such as are illustrated and described in U. S. Letters Patent to Wiggin-ton No. 1,174,458, issued March 7, 1916, and 15 I have shown one form of the binder illustrated in that patent in connection with my improvements.

My improvements are, however, capable of embodiment and are desirable for use 20 with other forms of temporary binders and in other relations where it is desirable to facilitate the handling of loose sheets.

The main objects of this invention are:

First, to provide an improved device 25 which facilitates the use of temporary binders or loose sheet holders and particularly those used in machine account systems.

Second, to provide an improved device 30 which facilitates the handling or manipulation of loose record sheets.

Third, to provide an improved device which facilitates the manipulation and handling of temporary binders and the insertion and removal of the sheets.

35 Further objects and objects relating to details and economies of construction and operation will definitely appear from the detailed description to follow.

I accomplish the objects of my invention 40 by the devices and means described in the following specification. The invention is clearly defined and pointed out in the claims.

A structure constituting a preferred embodiment of my invention is illustrated in 45 the accompanying drawing forming a part of this specification, in which:

Figure I is a perspective view of a structure embodying the features of my invention, 50 without a binder therein, the holder shown in partially collapsed position.

Fig. II is a view partially in vertical transverse section with the holder adjusted to support a binder in its closed position.

55 Fig. III is a view similar to Fig. II illus-

trating the holder supporting a binder with a less number of sheets than that shown in Fig. II.

Fig. IV is a view similar to Figs. II and III, showing the holder supporting a binder 60 with still fewer sheets.

Fig. V is a perspective view showing the holder members adjusted to receive the binder members and the binder members arranged therein, the sheets being arranged all 65 on one binder member.

Fig. VI is a transverse vertical section with the center or supplemental end member in position, a part of the sheets being shown on each binder member. 70

Fig. VII is a perspective view with the holder in its extended position and the supplemental end member in position.

Fig. VIII is a perspective view corresponding to that of Fig. I, of a slightly 75 modified embodiment of my invention.

Fig. IX is a detail perspective view of the embodiment shown in Fig. VIII, with the holder members extended, the supplemental end member being shown in a disassembled 80 relation thereto.

Fig. X is a transverse vertical section through the embodiment shown in Figs. VIII and IX, with the holder members shown in collapsed position in full lines and 85 in extended position by dotted lines.

Fig. XI is a detail vertical section illustrating the interchangeability of supplemental members.

In the drawings, similar reference characters refer to similar parts throughout the several views. 90

In the embodiment illustrated, I provide a rectangular base or frame comprising sides 1, 1, and ends 2, 2 supported upon legs 3. 95 The holder members, designated generally by the numerals 4 and 5, are pivoted at 6 between the end members of the frame or base. These holder members comprise the side members 7 and 8 and coacting end members 9 and 10, respectively. The end members and the side members of the structure illustrated are disposed at right angles to each other. The width of the end members is such that their edges clear when the 100 holder members are swung to their collapsed or extended positions.

The inner ends of the side members 7 and 8 are extended to provide stops 11 and 12, respectively. When the holder members are 110

swung to their extended position, as shown in Fig. VI, these stops engage the coacting stops 13 and 14 on the base or frame. When the holder members are fully collapsed, the 5 end member 10 engages the stop 14 while the end member 9 engages the stop 15. When swung to their erected position, as shown in Figs. I, II, III and IV, the side members 10 will engage the covers of the binder resting upon the end members supporting it in its closed position. The weight of the binder resting upon the end members tends to hold the binder closed.

In Figs. II, III and IV, it will be seen 15 that the holder automatically adjusts itself within its scope to binders of varying thickness. When the holder members are extended they provide a pair of V-shaped holders each adapted to receive one of the 20 binder members which I designate generally by the numeral 16.

These binder members are connected by binding strips 17 as is described in the patent referred to. The end members are trans- 25 versely slotted at 18 to receive these binding strips.

To complement or supplement the end members, I provide an A-shaped supplemental end or center member, designated generally by the numeral 19, having arms 20 and 21 secured to each other. The arm or part 20 of this center or supplemental end member is adapted to edge-abut with the end member 10, while the other part or arm 35 21 overlaps the end member 9, 9, and abuts the filler block 22, disposed in the angle of the holder member 4.

This center member is provided with hand 40 holes 23 and with dowels 24 connecting it with the end member 10. In the structure illustrated the part 21 when adjusted to position lies at an acute angle to the side 7, so that fanning or stepping of the upper edges of the sheets is secured to facilitate fingering.

In the modifications shown in Figs. VIII, 45 IX and X, a stop block 25 is mounted on the ends of the frame or base, the ends of the block being beveled to coact with the side stop extensions 11.

The supplementary end member 26 of this 50 embodiment is adapted to edge-abut both holder end members, as shown by dotted lines in Fig. X.

In Fig. XI, I illustrate the adaptation of 55 the end member 26 to the preferred embodiment shown.

By thus forming and arranging the parts, I secure a structure which may be readily 60 adjusted to provide a pair of V-shaped holders each adapted to receive a binder member with sheets resting thereon and the sheets transferred from one holder to the other or the device may be adjusted to support the binder in its closed position, as 65 illustrated.

My improved binder device greatly facilitates the manipulation of sheets and loose sheet holders or binders. I have not attempted to illustrate or describe certain modifications in structural details, which I 70 contemplate, as I believe the disclosure made will enable those skilled in the art to which my invention relates to embody or adapt the same as may be desired.

Having thus described my invention, what 75 I claim as new and desire to secure by Letters Patent is:

1. In a device of the class described, the combination of a rectangular frame, a pair of holder members each comprising side and end members disposed at right angles to each other and pivoted between the end members of said frame for adjustment to an outwardly or inwardly inclined relation, the width of the end members being such as 80 to permit them to clear when swung to and from their inner and outer positions, the inner ends of the side members being extended to provide stop engaging parts, stops coacting with such parts to support said holder members in their extended position and with said end members to limit the collapsing movement of said holder members, and a pair of removable interchangeable A-shaped supplemental end members, each having one arm adapted to edge-abut one end member, the second arm of one supplemental member being adapted to overlap the second end member, the second arm of the other supplemental member being adapted 85 to edge-abut the second end member. 90

2. In a device of the class described, the combination of a pair of holder members each comprising side and end members disposed at right angles to each other and pivotally mounted for adjustment to an outwardly or inwardly inclined relation, the width of the end members being such as to 100 permit them to clear when swung to and from their inner and outer positions, and a pair of removable interchangeable A-shaped supplemental end members, each having one arm adapted to edge-abut one end member, the second arm of one supplemental member being adapted to overlap the second end member, the second arm of the other supplemental member being adapted 105 to edge-abut the second end member. 110

3. In a device of the class described, the combination of a rectangular frame, a pair of holder members each comprising side and end members and pivoted between the end members of said frame for adjustment to 115 an outwardly or inwardly inclined relation, the width of the end members being such as to permit them to clear when swung to and from their inner and outer positions, the inner ends of the side members being ex- 120

125 130

- tended to provide stop engaging parts, stops coacting with such parts to support said holder members in their extended position and with said end members, to limit the collapsing movement of said holder members and a removable A-shaped supplemental end member. 5
4. In a device of the class described, the combination of a pair of holder members each comprising side and end members and pivotally mounted for adjustment to an outwardly or inwardly inclined relation, the width of the end members being such as to permit them to clear when swung to and from their inner and outer positions, and a removable A-shaped supplemental end member. 10
5. In a device of the class described, the combination of a pair of holder members each comprising side and end members disposed at right angles to each other and pivotally mounted for adjustment to an outwardly or inwardly inclined relation, the width of the end members being such as to permit them to clear when swung to and from their inner and outer positions, and a removable A-shaped supplemental end member having one arm adapted to edge-abut one end member and provided with dowel connections therefor, and the other arm adapted to overlap the other end member. 15
6. In a device of the class described, the combination of a pair of holder members each comprising side and end members disposed at right angles to each other and pivotally mounted for adjustment to an outwardly or inwardly inclined relation, the width of the end members being such as to permit them to clear when swung to and from their inner and outer positions, and a removable A-shaped supplemental end member having one arm adapted to edge-abut one end member and the other arm adapted to overlap the other end member. 20
7. In a device of the class described, the combination of a frame, a pair of holder members each comprising side and end members and pivotally mounted within said frame for adjustment to an outwardly or inwardly inclined relation, the end members being adapted to swing past each other, and a removable A-shaped supplemental end member. 25
8. In a device of the class described, the combination of a frame, a pair of holder members each comprising side and end members and pivotally mounted within said frame for adjustment to an outwardly or inwardly inclined relation, the end members being adapted to swing past each other, and a removable A-shaped supplemental end member. 30
9. In a device of the class described, the combination with a pair of holder members each comprising side and end members and mounted for adjustment to provide a pair of holders each adapted to receive a binder member with sheets resting thereon or to be swung to an upright position with the side members engaging the covers of a binder resting upon the end members, and a removable supplemental end member. 35
10. In a device of the class described, the combination with a pair of holder members each comprising side and end members and mounted for pivotal adjustment to provide a pair of holders each adapted to receive a binder member with sheets resting thereon or to be swung to an upright position with the side members engaging the covers of a binder resting upon the end members, and a removable supplemental end member. 40
11. In a device of the class described, the combination of a holder comprising a pair of members mounted for adjustment in oppositely inclined relation to provide a pair of holders each adapted to receive a binder member with sheets resting thereon or to an inwardly inclined relation to support a binder in its closed upright position and a removable supplemental end member. 45

In witness whereof, I have hereunto set my hand and seal in the presence of two 95 witnesses.
